CLAIM

The ornamental design for a medical device, as shown and described.

DESCRIPTION

This application is related to U.S. application Ser. Nos. 29/639249, 29/639258, 29/639287, 29/639289 and 29/639259, all filed Mar. 5, 2018, the entire disclosures of which are hereby incorporated herein by reference.

FIG. 1 is a front perspective view of a medical device showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a rear perspective view thereof; and,

FIG. 9 is another front perspective view thereof, the front perspective view of FIG. 9 being similar to the front perspective view of FIG. 1 but for the depiction in broken lines of unclaimed environmental structure in FIG. 9.

The broken lines in FIGS. 1-3 and 6-8 depict portions of the medical device that form no part of the claimed design.

The broken lines in FIG. 9 depict portions of the medical device that form no part of the claimed design, and also depict environmental structure that forms no part of the claimed design.

The different surface shadings (line shading and stippled shading) in FIGS. 1, 8, and 9 are used to indicate contrasting materials.
